UNITED STATES PATENT OFFICE.

LYMAN W. WELCH, OF GRAND RAPIDS, MICHIGAN.

REVOLVING-RACK SHOW-CASE.

1,104,156.

Specification of Letters Patent. Patented July 21, 1914.

Application filed June 6, 1913. Serial No. 772,069.

To all whom it may concern:

Be it known that I, LYMAN W. WELCH, a citizen of the United States, residing at Grand Rapids, Michigan, have invented certain new and useful Improvements in Revolving-Rack Show-Cases, of which the following is a specification.

This invention relates to improvements in revolving rack show cases.

10 The invention relates particularly to a revolving rack for a show case for hats or other small articles.

15 The objects of the invention are to provide a simple, efficient and compact structure for displaying hats.

The specific object of the invention is to provide an improved revoluble rack for show cases of the type illustrated in my patent of April 16, 1912, No. 1,023,186.

20 Objects pertaining to details will definitely appear from the detailed description.

I accomplish the objects of my invention by the devices and means described in the following specification. The invention is

25 clearly defined and pointed out in the claims.

A structure constituting a preferred embodiment of my invention is fully illustrated in the accompanying drawing, forming a part of this specification, in which:

30 Figure I is a detail sectional elevation of my improved show case, taken on a line corresponding to line 1—1 of Fig. II, the rack being in full lines. Fig. II is a sectional plan view taken on a line corresponding to line 2—2 of Fig. I, the rack being in full

35 lines with a part broken away. Fig. III is a detail sectional elevation view taken on a line corresponding to line 3—3 of Fig. I. Fig. IV is an enlarged detail view of one of

40 the channel frame bars, showing the method of attaching the hat supports. Fig. V is an enlarged detail transverse sectional view, taken on a line corresponding to line 5—5 of Figs. II and IV, showing details of construction of the pivotal parts and of the

45 hinging of the said hat supports. Fig. VI is a detail sectional view taken on a line corresponding to line 6—6 of Fig. IV, showing details of the pivotal arm support construction.

50 Fig. VII is a detail sectional view taken on line 7—7 of Figs. I and VIII, showing details of connection of the horizontal bars with the vertical columns. Fig.

55 VIII is a detail sectional view on line 8—8 of Figs. I and VII, showing the similar details. Fig. IX is a detail perspective view

of one end of the horizontal bar 12, showing the end construction and also the hat supporting loops.

In the drawing, all the sectional views are taken looking in the direction of the little arrows at the ends of the section lines, and similar numerals of reference refer to similar parts throughout the several views.

Considering the numbered parts of the drawing, the case 1 is oblong in form, having front doors 2, 2 adapted to slide in ways 3, 3 at each side in the floor 4. The floor 4 is supported on side joists or beams 5, 5, and central joists 6, 6 forming a channel 7 extending from front to rear of the case. In this channel the carriage 8 reciprocates, carrying the vertical shaft or hub 9 on which the base cross bar 10 is journaled to revolve. These parts are the same as those appearing in my former patent referred to. There is further provided oblique guards 10', 10' at each side, to prevent contact of the revolving rack with the case while it is being manipulated and revolved and moved out and into the case. The base bar 10 is provided with a pair of vertical columns 11, 11, one at each end, also, as in my former structure referred to.

My improved hat rack is made up of a series of suitably spaced parallel bars 12, channel in form, with side flanges 12' and 13, one above another, disposed with the flanges 12' projecting downward, suitably perforated at 18, the flanges 12' contacting with the sides of the columns to clamp and embrace these upright columns 11. These channel bars 12 are properly spaced and held adjustable in place by transverse bolts 19 in proximity to the columns 11 and provided with screw nuts 20 to clamp the flanges against the outer surface of the columns 11.

In the tops of the channel frame bars are disposed suitable pivoted hat supports 14, made of a doubled rod somewhat like a hairpin in form, with the inner ends 16 offset downwardly and projecting into apertures 17 in the tops of the said channel bars especially adapted to receive the same. Upwardly offset portions 15, 15 are disposed to receive and retain the hats effectively in place when disposed thereon.

From this description, it will be seen that my improved structure is very simple and effective. While channel bars are made use of, they are disposed in such a way as to

give a massive effect without causing undue weight of the parts, lightness being very desirable in a structure which is intended to handle so light a burden as hats. The channel shape of the bars provides a very rigid construction which is of such shape that it can be very readily perforated and effectively hold the hat supports. The ends 13 of each bar being folded down, see Fig. IX, 10 give a very finished appearance.

Several modifications have been shown and others can readily be devised. I desire to claim the structure broadly and also specifically, as pointed out in the appended 15 claims.

Having thus described my invention, what I claim as new and desire to secure by Letters Patent is:

1. In a revolving rack show case for hats, 20 the combination of a carriage and a base bar pivotally supported on said carriage, vertical columns at each end of said base bar, a rack consisting of a series of spaced channel bars perforated and disposed on 25 said columns with their flanges downward, said columns passing through said perforations, clamping bolts extending through

said flanges on both sides of said columns adjacent thereto, and doubled rod supports with portions upwardly offset to receive and 30 retain the hats, the inner ends of the rods being downwardly offset and disposed in apertures in said bars, as specified.

2. In a revolving show case for hats, the combination of a carriage, a base bar pivotally supported on said carriage, a vertical column on said base bar, a rack consisting of a series of channel bars, said channel bars being provided with suitable openings for the passage of said column and disposed upon said column with their flanges extending downwardly, and clamping bolts extending through said flanges adjacent to the column whereby said flanges may be drawn together to clamp the channel bars upon 40 said column, all coacting substantially as described for the purpose specified.

In witness whereof, I have hereunto set my hand and seal in the presence of two witnesses.

LYMAN W. WELCH. [L.S.]
